(57) **CLAIM**

The ornamental design for a pill crusher for one-handed use, as shown and described.

DESCRIPTION

FIG. 1 is a top front perspective view of the pill crusher for one-handed use;

FIG. 2 is a bottom rear perspective view thereof;

FIG. 3 is a top plan view thereof;

FIG. 4 is a left-side elevation view thereof;

FIG. 5 is a rear elevation view thereof;

FIG. 6 is a right-side elevation view thereof;

FIG. 7 is a front elevation view thereof; and,

FIG. 8 is a bottom plan view thereof.

In the drawings, the broken lines depict unclaimed subject matter only and form no part of the claimed design.
